FRANK CONRAD, OF PITTSBURGH, AND CHARLES E. WILSON, OF WILKINSBURG, PENNSYLVANIA, ASSIGNORS TO WESTINGHOUSE ELECTRIC AND MANUFACTURING COMPANY, A CORPORATION OF PENNSYLVANIA.

STARTING MECHANISM FOR AUTOMOBILES.

1,246,057.

Specification of Letters Patent.

Patented Nov. 13, 1917.

Application filed April 6, 1915. Serial No. 19,469.

To all whom it may concern:

Be it known that we, FRANK CONRAD, a citizen of the United States, and a resident of Pittsburgh, in the county of Allegheny and State of Pennsylvania, and CHARLES E. WILSON, a citizen of the United States, and a resident of Wilkinsburg, in the county of Allegheny and State of Pennsylvania, have invented a new and useful Improvement 10 in Starting Mechanism for Automobiles, of which the following is a specification.

Our invention relates to starting mechanisms for automobiles and particularly to such mechanisms as embody dynamo-electric machines having reciprocating parts for actuating pinions into and out of operative connection with the shafts of internal combustion engines.

20 Our invention has, for one of its objects, to provide a simple and efficient means whereby a starting motor may be operatively connected to the shaft of an internal combustion engine by the reciprocation of parts of comparatively light weight.

25 A second object of our invention is to provide a simple arrangement whereby an operative connection may be established between the armature of a dynamo-electric 30 machine and an engine shaft, while little or no torque is effective to rotate the armature.

It has been proposed to employ motors 35 having displaced armatures which reciprocate to effect the meshing of coacting gear wheels, but they possess certain disadvantages, in that they require the use of complicated switching mechanisms and resistors to prevent rotation of the armature until 40 the gear wheels are placed in mesh. This arrangement is necessary because, in the displaced position of the armature, the torque is sufficiently high to rotate the armature at a comparatively high rate of speed 45 before the gear wheels are completely meshed.

In the operation of motors having displaced armatures, the reciprocating parts are very heavy and the shock resulting 50 from the engagement of the parts, in case the coacting gear teeth are not in register, may seriously damage the gear teeth. An excessively long commutator must be provided in order that the brushes will be in

engagement with it throughout the path of movement of the armature.

According to the present invention, we provide an electric motor having a tubular armature shaft, in the bore of which a rod is mounted for longitudinal slidable movement. The rod is connected to a pinion that is slidably mounted on the armature shaft for rotation therewith. The slidable rod is controlled by an electromagnet that is in series with the field magnet winding 60 of the motor. The rotation of the motor armature is temporarily delayed by the employment of a short-circuited damper winding which prevents a sudden increase in the intensity of the magnetic field of the 65 motor upon the closing of its circuit.

The details of our invention will be described in connection with the accompanying drawings in which Figure 1 is a side view, partially in elevation and partially 70 in section, of a portion of an engine fly wheel with our invention applied thereto. Fig. 2 is a diagrammatic view of circuits and apparatus embodying our invention.

Referring particularly to Fig. 1, an engine fly wheel 1, only a portion of which is shown, is provided with gear teeth 2. An electric motor 3 has a field-magnet frame 4 which may be secured to any suitable stationary part of a motor vehicle. The motor has field-magnet poles 5, each of which is provided with a coil 6 of a series field winding and a short-circuited coil 7 of a 80 damper winding.

The motor armature 8 has a shaft 9 that 90 is provided with a longitudinally extending bore 10. A rod 11, which is mounted for slidable movement therein, is connected, at one end, to a pinion 12 by means of a collar member 13 and nuts 14. The pinion 12 is 95 slidably mounted on a portion 15 of the armature shaft 9 that is square in cross section, for rotation therewith. The position of the rod 11, relatively to the armature shaft 9, is controlled by an electromagnet 16 that is located in an extended portion 17 of the motor casing and is in axial alignment 100 with the armature shaft 9.

The electromagnet 16 comprises a coil 18 that is in series with the series field winding 105 6 of the motor. The rod 11 is provided with an enlarged portion 19 which constitutes the movable core member of the electromagnet.

A spring 20, which is interposed between the core member 19 and one end of the casing 17, tends to maintain the rod 11 in such a position that the pinion is disengaged from the gear teeth 2. The motor is provided with a terminal member 21 which is connected to the coil 18 of the electromagnet. The other terminal of the coil 18 is connected to the motor windings by a suitable conductor 22.

The electrical connections of the motor and the electromagnet are diagrammatically illustrated in Fig. 2. The motor may have, for example, four poles, each of which is provided with a series field coil 6 and a short-circuited coil 7 which constitutes a damper winding. The motor circuit comprises the coil 18 of the electromagnet, a switch 23 and a storage battery. One of the battery terminals and one of the motor terminals are grounded, a single-wire system being employed.

To start the engine, the operator closes the switch 23 to complete the motor circuit. Current then flows from the ungrounded side of the battery through the switch 23, the coil 18, motor armature 8 and series field coils 6 to ground, and thence back to the grounded side of the battery. The coil 18 is immediately energized to actuate the core member 19, the rod 11 and the pinion 12 to the left, as viewed in Fig. 1, against the force of the spring 20. The series field coils 6 will also be energized, but a sudden increase in the flux traversing the field magnet poles 5 is opposed by the short-circuited coils 7.

The damping effect of the coil 7 occurs only during such time as the flux tends to increase. The effect is, therefore, to materially limit the flux when the circuit is initially closed so that a very slight torque, if any, is effective to rotate the pinion 12 while it is being meshed with the gear teeth 2. It has been found, in practice, that the normal torque of the motor is available substantially upon the complete meshing of the coacting gear teeth. The fly wheel is therefore upon rotated to crank the engine.

When the engine starts under its own power, the motor circuit may be broken at the switch 23. The coil 18 is then deenergized, and the spring 20, which has been compressed, will then return the core member 19, the rod 11 and the pinion 12 to their respective illustrated positions, with the pinion disengaged from the fly wheel 1.

If the operator fails to open the motor circuit immediately after the engine starts, the motor will be driven at a rapidly increasing speed. The counter electromotive force of the motor is thereby increased to reduce the current traversing its circuit to such value that the pull exerted by the coil 18 is less than the force of the spring 20, whereupon

the rod 11 is shifted to its normal position and the pinion 12 is disengaged from the gear teeth 2. It is obvious, therefore, that no damage may be caused by a failure to open the switch at the proper time.

Among other advantages possessed by a mechanism constructed in accordance with our invention, it may be noted that the reciprocating parts are light in weight and are not an essential part of a dynamo-electric machine. Because of this latter fact, it is not necessary to provide a commutator of abnormal length or to rearrange the motor casing and bearings. The mechanism operates automatically upon the closing of a single switch to effect the meshing of the pinion with the fly wheel gear while little or no torque is effective to rotate the pinion, and the normal torque is effective when the gear wheels are completely meshed.

While we have shown and described a specific embodiment of our invention, it is understood that such modifications may be made as fall within the scope of the appended claims without departing from the spirit of our invention.

We claim as our invention:

1. In a starting mechanism, the combination with an electric motor having a hollow shaft, a rod within said shaft, and a pinion rotatable with said shaft and connected to said rod for endwise movement therewith, of an electromagnet in series with said motor for controlling the position of said rod relatively to the shaft, and means for temporarily retarding the operation of the motor upon the closing of its normal circuit.

2. In a starting mechanism, the combination with an engine gear wheel, an electric motor, and a gear wheel connected to said motor for coacting with the engine member, of an electromagnet for effecting the meshing of said gear wheels, a switch for controlling the motor and the electromagnet, and means independent of said switch for temporarily retarding the operation of said motor upon the closing of its normal circuit.

3. In a starting mechanism, the combination with an engine, a gear wheel connected thereto, an electric motor, and a pinion for operatively connecting said motor to said gear wheel, of means in circuit with the motor for controlling the engagement of said pinion with the gear wheel, and means for temporarily modifying the operation of the motor automatically upon the closure of its normal circuit.

4. In a starting mechanism, the combination with an engine member, an electric motor, and a pair of relatively movable gear wheels for operatively connecting said motor to said engine member, of means in series with the motor for controlling the engagement of said gear wheels, and means for temporarily modifying the operation of the

motor automatically upon the closure of its normal circuit in order that the meshing of said gear wheels may be effected before normal torque is applied to the armature of said 5 motor.

5. In a starting mechanism, the combination with an engine member, an electric motor, and a pair of relatively movable gear wheels for operatively connecting said motor 10 to said engine member, of means in circuit with the motor for effecting the meshing of said gear wheels, and a time-element device for controlling the torque of said motor upon the closure of its normal circuit.

15. 6. In a starting mechanism, the combination with an engine member, an electric motor, and a pinion for operatively connecting said motor to said engine member, of means in circuit with the motor for controlling the 20 engagement of said pinion with the engine member, and means for temporarily damping the field flux of said motor upon the closure of its circuit.

7. In a starting mechanism, the combination with an engine member, an electric motor, and a pinion for operatively connecting said motor to said engine member, of means in circuit with the motor for controlling the engagement of said pinion with the engine 30 member, and means comprising a short-circuited winding for temporarily controlling the intensity of the magnetic field of the motor upon the closure of its circuit.

8. In a starting mechanism, the combination with an engine member, a gear wheel connected thereto and a shiftable member for coacting therewith, of electro-responsive devices connected in series with a source of energy for actuating the shiftable member into 40 and out of engagement with said gear wheel and for rotating said shiftable member, and automatic means for temporarily

modifying the operation of the rotatable device automatically upon the closure of its normal circuit.

45

9. In a starting mechanism, the combination with an engine, a gear wheel operatively connected thereto, an electric motor, and a pinion that is longitudinally shiftable relatively to said armature but is rotatable therewith, of electro-responsive means in series with said motor for shifting said pinion into mesh with said gear wheel, and means for retarding the operation of said motor temporarily upon the closure of its normal circuit.

50

10. In a starting mechanism, the combination with an engine member, an electric motor, and a pinion for operatively connecting said motor to said engine member, of means in circuit with the motor for controlling the engagement of said pinion with the engine member, and electro-responsive means inductively related to one of the motor windings for temporarily preventing the 60 normal energization of one of the motor parts upon the closure of the motor circuit.

65

11. In a starting mechanism, the combination with an engine, a series-wound electric motor, and means for operatively connecting said motor to said engine, of means in circuit with said motor for controlling the engagement of said connecting means, and means inductively related to the field-magnet winding of said motor for temporarily 70 preventing the normal energization of the magnetic field of the motor upon the closure of its circuit.

75

In testimony whereof, we have hereunto subscribed our names this 31st day of March, 1915.

80
